Inventor:

Christopher W. Bauer,
By his Attorney,
Leo W. Nieth

UNITED STATES PATENT OFFICE.

CHRISTOPHER W. BAUER, OF BROOKLYN, NEW YORK.

HOUSEHOLD IMPLEMENT.

1,402,470.

Specification of Letters Patent. Patented Jan. 3, 1922.

Application filed October 5, 1920. Serial No. 414,828.

To all whom it may concern:

Be it known that I, CHRISTOPHER W. BAUER, a citizen of the United States, and a resident of the borough of Brooklyn, county 5 of Kings, city and State of New York, have invented certain new and useful Improvements in Household Implements, of which the following is a specification.

The object of my invention is to afford a simple, cheap, but effective unitary implement that may be conveniently used for various household purposes; for instance, as a door or window check or securing device; as a can opener; as a bottle cap remover; as 10 a pry for opening boxes, etc.; as a wrench; and for numerous analogous purposes;—the invention consisting of an integral metallic structure of the specific character described and claimed herein; and a distinctive feature being the utilization, as a bottle cap remover, of the space and edges created in the blank by the formation of the can-opening means, all as hereinafter fully set forth.

In the accompanying drawings, 25 Fig. 1 is a perspective view of my improved conjoined implement;

Fig. 2 is a view of the flat metallic blank as die struck, and before the bending thereof;

30 Fig. 3 is an edge view of the blank shown in Fig. 2;

Fig. 4 is an edge view of the blank as bent to form the completed implement;

Fig. 5 is a top view of the implement projected from Fig. 4;

Fig. 6 is a sectional view of the implement taken upon plane of line 6—6, Fig. 5, and illustrating the use thereof as a bottle opener;

40 Fig. 7 is a view illustrating the use of the device as a pry lever; and

Fig. 8 is a sectional view illustrating the use of the implement as a can opener or sheet-metal cutter.

45 My household implement consists primarily and essentially of a flat strip of suitable metal such as wrought iron, steel, or any other metal or alloy adapted for the purpose, die-stamped into the shape shown 50 in Figs. 2 and 3, and then bent and sharpened as requisite in the formation of the complete device.

55 Thus one extremity of what may be designated as the body or handle H of the implement is bifurcated, or claw shaped, being formed with the pointed claws c, c, and

being bent over at an angle as shown, while the other extremity is rectangular, and is bevel-ground transversely to form a wedge w, which may be used as a pry, as indicated in Fig. 7, or inserted under a door d, as indicated in Fig. 4, in which latter case the other or bifurcated extremity C of the device acts as a dog or claw to sustain the device firmly in the required position and 60 to counteract back pressure,—the transversely beveled edge w constituting the apex of the incline thus afforded by the main portion H of the plate. In this connection it is obvious that the implement may be used 65 in a similar manner to jam and prevent the opening of the lower sash of a window, and also for various analogous purposes.

Near its beveled end w, the handle H may be formed with an opening n, adapting the 75 device for use as a nut wrench or for analogous purposes,—the said opening n being formed with offsets of different width to accommodate nuts, bolt-heads, or the like, 80 of various sizes.

The claw end of the plate H is formed with a bottle-cap opening b, having convergent side edges b', and a lower curved edge b'', formed preferably with inwardly protuberant lugs b³, b³ for contactual 85 engagement with the edge of a bottle cap k, as indicated in Fig. 6,—the convergent side edges b', b'' being adapted to bear against the top of said bottle cap k during the loosening operation, in which 90 latter case the body H of the device is used as a handle.

The creation of the bottle-cap opening b in the claw end of the device also forms a cross-bar a, which braces the claws c, c. 95

A portion of the metal involved in the formation of the bottle-cap opening b is utilized in the construction of the can-opening means, consisting of the cutter jaw j and the bearing jaw j', the shanks of which 100 form continuations of the plane of the main plate H, and the bending of the claw end C of the device leaving the outer portions of the jaws j, j' free and unobstructed, and available for use in the cutting of sheet 105 metal in a manner well known in the can-opener art. The free end of the bearing jaw j' is formed with lateral extensions, the twisting of which forms a broad fulcrum bearing j², opposed to the hooked and pointed cutting blade or jaw j. Both these jaws j and j' if preferred may be separate pieces 110

of metal the shanks of which are riveted or otherwise integrally secured to the main plate or handle H, as indicated by dotted lines in Fig. 5.

5 I have herein set forth some of the uses to which my conjunctive implement may be applied. It is obvious that there are many other analogous purposes or exigencies in which the device would be available, thus 10 rendering it of general utility as an emergency contrivance. Furthermore, it is simple and inexpensive, there are no movable parts, and nothing to get out of order, the whole structure being unitary and rigid.

What I claim as my invention and desire to secure by Letters Patent is,

A device for the purpose described formed of a single plate of flat metal and comprising a body portion and a portion at an angle thereto and having an opening, and jaws in 20 said opening at the bend of the metal, one of said jaws being a cutter, and the other twisted to form a broad fulcrum bearing.

CHRISTOPHER W. BAUER.
